JOHN CORRIGAN, OF CHARLESTOWN, MASSACHUSETTS.

Design No. 3,266, dated December 1, 1868.

DESIGN FOR AN AXLE-BOX FOR RAILWAY-CARRIAGES.

The Schedule referred to in these Letters Patent and making part of the same.

To all whom it may concern:

Be it known that I, JOHN CORRIGAN, of Charlestown, in the county of Middlesex, and State of Massachusetts, have originated and designed a new Pattern for Axle-Boxes for Railway-Carriages, of which the following is a full, clear, and exact description, reference being had to the accompanying drawings, making a part of this specification.

A A represent a box, with a sliding door, B, spring, C, the lugs *g g*, and the grooves *a a*.

What I claim as my invention, and desire to secure by Letters Patent, is—

The design or pattern for an axle-box for railway-carriages, herein set forth.

JOHN CORRIGAN.
